(57) **CLAIM**

The ornamental design for a dual elastic hose, as shown and described.

DESCRIPTION

FIG. 1 is a top perspective view of a dual elastic hose shown in a disassembled state for ease of illustration;

FIG. 2 is a front view, the back view being mirror image thereof;

FIG. 3 is a left view thereof;

FIG. 4 is a right view thereof;

FIG. 5 is a top view thereof;

FIG. 6 is a bottom view thereof;

FIG. 7 is an enlarged sectional view of portion 7 of FIG. 1; and,

FIG. 8 is an enlarged detail view of portion 8 of FIG. 2. The hose is shown with a symbolic break in its length. The appearance of any portion of the hose between the break lines forms no part of the claimed design. The broken lines shown in the drawings depict portions of the dual elastic hose that form no part of the claimed design.
